(57) **CLAIM**

The ornamental design for a washer game, as shown and described.

DESCRIPTION

FIG. 1 is a perspective view of a washer game showing my new design;

FIG. 2 is a top plan view of the first of the pair of targets;

FIG. 3 is a front elevation view thereof;

FIG. 4 is a bottom plan view thereof;

FIG. 5 is a left side elevation view thereof;

FIG. 6 is a rear elevation view thereof;

FIG. 7 is a top plan view of the second of the pair of targets;

FIG. 8 is a front elevation view thereof;

FIG. 9 is a left side elevation view thereof;

FIG. 10 is a bottom plan view thereof; and,

FIG. 11 is perspective view of the pair of targets nested together in an assembly.

The broken lines showing of ground surface and washers are for illustrative purpose only and form no part of the claimed design.
